Primary Examiner — Cynthia M. Chin(74) *Attorney, Agent, or Firm* — Michael Best & Friedrich LLP(57) **CLAIM**

The ornamental design for a UTV ride-on toy, as shown and described.

DESCRIPTION

FIG. 1 is a front perspective view of the design; FIG. 2 is a rear perspective view of FIG. 1; FIG. 3 is a front elevational view of FIG. 1; FIG. 4 is a rear elevational view of FIG. 1; FIG. 5 is a left-side elevational view of FIG. 1; FIG. 6 is a right-side elevational view of FIG. 1; and, FIG. 7 is a top plan view of FIG. 1. The broken lines show portions of the UTV ride-on toy that form no part of the claimed design.
